UNITED STATES PATENT OFFICE.

JOHN OLSON, OF CLEARFIELD, PENNSYLVANIA.

RAILWAY-TIE AND FASTENER.

1,152,206.

Specification of Letters Patent. Patented Aug. 31, 1915.

Application filed May 12, 1915. Serial No. 27,570.

To all whom it may concern:

Be it known that I, JOHN OLSON, a citizen of the United States, residing at Clearfield, in the county of Clearfield and State of Pennsylvania, have invented certain new and useful Improvements in Railway-Ties and Fasteners; and I do hereby declare the following to be a full, clear, and exact description of the invention, such as will enable others skilled in the art to which it applies to make and use the same.

This invention relates to new and useful improvements in railway ties and fasteners and the principal object of the invention is to provide a tie which may be made of metal and to which railroad rails may be easily and quickly secured to prevent the same from spreading or sinking.

Another object of the invention is to provide a tie which may be made of metal and which is so constructed as to render the removal of the railroad rails comparatively easy and which will also prevent the rails from becoming accidentally detached.

A further object of the invention is to provide a device which if so desired may be so constructed as to be used as a cap for the ordinary wooden tie to which the rails may be rigidly secured.

Still another object of the invention is to provide a railway tie provided near each end with recesses having overhanging rail flange engaging portions for the reception of the rails and to provide fasteners arranged to be connected to the tie bodies and coöperate with the overhanging portions in holding the rails against displacement.

A still further object of the invention is to provide a tie of the above character which is so constructed as to enable the rail fasteners to be removed without necessitating the removal of the rails from the tie, thereby enabling the user to easily and quickly substitute a new fastener for one which may be broken or worn.

With these and other objects in view, the invention consists in the novel combination and arrangement of parts which will be fully set forth in the following specification and accompanying drawings, in which:

Figure 1 is a plan view of a railroad tie constructed in accordance with this invention. Fig. 2 is a side view in elevation of the tie showing the rails in place, the said rails being in section. Fig. 3 is a fragmentary perspective view of the tie. Fig. 4 is

a fragmentary perspective view of the fastener, and Fig. 5 is a sectional view on line 5—5 of Fig. 2.

Referring now to the drawings by characters of reference, the numeral 1 designates as an entirety a tie constructed in accordance with this invention comprising the body 2 having formed in its upper face near each end suitable recesses 3. A longitudinally extending groove 4 connects the recesses and forms the upstanding longitudinal flanges 5 which project upwardly one each side of the tie. The outer faces of these flanges 5 are coincident with the side faces of the body 2 and these flanges are each provided with the transverse horizontally extending openings 6, the use of which will appear as the description proceeds. The recesses 3 extend entirely across the tie as shown and form the end wall or shoulder 7, as clearly illustrated in Fig. 3. Formed at the upper edge of the shoulder and extending therefrom in a direction opposite to the recess 3 is the rail seat 8, which is formed by notching out the body of the tie as clearly shown. Co-operating with the rail seat 8 is the rail flange engaging portion 9 which partially overhangs said rail seat and is arranged to engage the upper side of the outer flange of the rail when the same is in place. The outer faces of each of the flanges 5 are provided with the counter-sunk recesses 10 in which the bolt heads and nuts rest as shown in Fig. 5.

Co-operating with the tie previously described are the rail fasteners best illustrated in Fig. 4, each of which comprises the body or head 11 having formed thereon the stem or shank 12. This shank or stem is provided with a pair of transversely extending apertures 13 which align with the apertures 6 to form bolt receiving passages through which the fastening bolts, which will be more fully hereinafter described, extend. The forward edge of the head 11 is notched out to form the rail seat 14 and is so constructed as to provide the rail flange engaging portion 15 which overhangs the inner flange of the rail when the same is in place. The rail seat 14 extends beyond the flange engaging portion 15 to provide the shoulder or abutment 16 which rests against the shoulder 7 when the device is in its assembled position. It will be noted that the shank or stem 12 is offset with relation to the center of the head 11 so that the inner

wall thereof lies in the same plane as the longitudinal axis of the rail fastener. The said stem being square in cross section so that when the two rail fasteners are in co-
operative position, they will exactly fit the groove 4 as clearly shown in Figs. 1 and 2.

In order to secure the rail fasteners within the tie, the fastening bolts 17 are provided and the heads 18 of the said bolts are seated in the counter-sinks on one side of the tie while the nuts 19 of said bolts seat in the counter-sink on the opposite side. It will be seen that the side faces of the ties are plane and there are no projections. It is also apparent that the ends of the bolts are protected against breakage and also against the elements so that there is little danger of the nuts becoming rusted thereon to certain extent as to prevent the removal of the bolts and the fasteners. The rails used in connection with this tie are of the ordinary type comprising the heads 20, provided with the centrally depending webs 21, which are provided at their lower edges with the rail bases 22, the outer and inner flanges of the rail bases being designated respectively A and B.

When assembling the tie and laying out the road, the ties are placed in the usual way and the rails slipped in place so that the flanges A rest on the rail seat 8 of the tie and are engaged by the flange engaging portions 9. The fasteners are then slipped in place by passing the rail seat 14 beneath the flanges B in such a way that the rail flange engaging portions 15 overhang the upper faces of the flanges B and the stems or shank 12 of the fasteners lie in the groove 4 and between the flanges 5 of the tie. In this position it will be seen that the openings 6 and 13 will align, thus allowing the passage of the bolts 17 therethrough, so that the heads 8 may be placed in the counter-sink 10 on one side of the tie and the nut 19 placed in the counter-sink on the opposite side of the tie. Upon tightening the nuts it will be apparent that accidental movement of the fasteners and rails is prevented and it will be apparent that the rails will be rigidly supported on the tie thereby avoiding any possibility of the rails twisting,

spreading or sinking, as the use of spikes is eliminated. It is apparent that a rail fastener constructed in accordance with this invention may be used in conjunction with a wooden tie by reducing the thickness of the body 2 and securing the body to the upper surface of the wooden tie. In using this device it is apparent that the rails will be more securely held in place than is possible by the ordinary method of spiking and it is also evident that when so used the combined advantage of the wooden and metallic ties is obtained.

While in the foregoing there has been shown and described the preferred embodiment of this invention, it is to be understood that such changes may be made in the combination and arrangement of parts as will fall within the spirit and scope of the appended claim.

What is claimed is:—

A railroad tie of the character described including a body having a recess near each end, rail seats formed adjacent the recesses, said rail seats being on a plane slightly above the bottom wall of the recesses and forming shoulders, rail flange engaging portions partly overhanging the rail seats, flanges extending upwardly from the sides of the tie forming a longitudinal groove connecting the recesses, tie fasteners arranged to seat in the recesses, said fasteners comprising a head, the head being notched to provide a rail seat and rail flange engaging portions, the edge of the bottom wall of the rail seat abutting its respective shoulder, a shank on the side of the head opposite the notched portion, the shanks of these fasteners lying adjacent each other, the flanges on the tie and the shanks being provided with alining apertures and bolts extending through the apertures to hold the shanks in place and thereby insure the rail fasteners against movement.

In testimony whereof I affix my signature in presence of two witnesses.

JOHN OLSON.
